US00D767145S

(12) **United States Design Patent** (10) Patent No.: **US D767,145 S**
(45) Date of Patent: **** Sep. 20, 2016**

(54) **FINGER-CLIPPED OXIMETER**

(71) Applicant: **Beijing Choice Electronic Technology Co., Ltd.**, Beijing (CN)

(72) Inventors: **Shuhai Liu**, Beijing (CN); **Hongliang Liu**, Beijing (CN)

(73) Assignee: **Beijing Choice Electronic Technology Co., Ltd.**, Beijing (CN)

(**) Term: **15 Years**

(21) Appl. No.: **29/527,336**

(22) Filed: **May 18, 2015**

(30) **Foreign Application Priority Data**

Nov. 18, 2014 (CN) 2014 3 0454457

(51) LOC (10) Cl. **24-01**

(52) U.S. Cl.

USPC **D24/169**
